UNITED STATES PATENT OFFICE.

THOMAS D. HODGE, OF DULUTH, MINNESOTA.

DISTRIBUTING A PULVERULENT LINING IN A SOAKING-PIT.

1,281,570.

Specification of Letters Patent. Patented Oct. 15, 1918.

Application filed October 25, 1917. Serial No. 198,440.

To all whom it may concern:

Be it known that I, THOMAS D. HODGE, a citizen of the United States, and resident of Morgan Park, Duluth, in the county of St. Louis and State of Minnesota, have invented certain new and useful Improvements for Distributing a Pulverulent Lining in a Soaking-Pit, of which the following is a specification.

10 In the operation of soaking-pits in steel works, it is necessary that a layer of fine coke be placed in the bottom of the pit upon which the ingots may rest.

It is customary to shovel this coke into 15 the pits by hand and then scrape or poke it into place. This is an extremely hot and laborious task, and it is difficult for the workmen to place the coke in the bottom of the pit to the best advantage. It is desirable 20 that the coke be thrown against the walls of the pit for the purpose of protecting the latter. At the same time it is desirable that the coke be so placed as to make a trough 25 for the accumulation of slag and also provide properly formed seats for the placing of the ingots in the pits. It is very important also that the distribution of the coke dust over the bottom be uniform, that is to say, it should not be piled high on one 30 side and low on the other.

One of the objects, therefore, of my invention is to facilitate the proper covering of the bottom of soaking-pits.

Another object is to preserve the walls of 35 soaking-pits.

Another object is to deposit coke dust in the soaking-pits in a manner to properly accumulate all the slag.

Generally speaking, these and other objects are accomplished by providing a portable hopper for discharging coke dust into 40 soaking-pits, including a bottom for causing the contents of the hopper to be discharged toward the walls and toward the middle of 45 the pit.

The invention is illustrated on the accompanying sheets of drawings, in which—

Figure 1 is a sectional elevation of my hopper shown in connection with a soaking- 50 pit; and,

Fig. 2 is a plan view of the hopper on an enlarged scale.

The various novel features of the invention will be apparent from the following description and drawings and will be particularly pointed out in the appended claims. 55

My hopper 10 is provided with a rectangular body portion including four walls 11, 12, 13 and 14, the lower portions of which converge downwardly. The body 60 portion of the hopper is divided into four chambers by intersecting partitions 15 and 16. At the lower end of one of the partitions 15 are downwardly diverging shedding portions 17. Secured to opposite sides of 65 the body portion of the hopper are laterally extending arms or frames 18 and 19 which are adapted to rest upon pit rails 20 and 21, respectively.

The hopper is adapted to swing from a 70 crane by means of a bail 22 secured to two pieces 23 which are connected to each other in intersecting planes. These two pieces 23 carry vertically extending members 24, to the lower ends of which members is secured 75 the hopper bottom 25. This hopper bottom includes two spaced peaked members 26, each of which is adapted to shed the contents of the hopper in laterally opposite directions toward the walls 27 and toward the middle 80 of the soaking-pit 28 over which the hopper proper may be deposited. The bottom of the hopper is removable downwardly from the body portion of the hopper, whereby the contents of the hopper may be deposited 85 readily into the pit 28.

By means of a crane, the hopper is carried to the pit loaded with coke dust and lowered into a position such that its laterally extending supporting frames or arms 18 and 90 19 rest upon the pit rails 20 and 21, respectively. When the crane lowers an increased amount after the hopper rests upon the pit rails 20 and 21, the bottom of the hopper moves downwardly from the main 95 body portion of the hopper, whereupon the coke dust rushes out from the hopper in a guided manner. The coke dust which passes outwardly over the sides of the peaks 26 in the bottom is charged against the side 100 walls of the pit to protect the same against the cutting action of the slag and the heat radiated from the hot ingots which later are deposited in the pit. At the same time

the coke dust which is discharged inwardly over the inner shedding surfaces of the peaks 26 is directed toward the middle of the pit. As a result of this guided discharge of the coke dust from the hopper, the coke dust is piled somewhat higher at the sides and at the middle of the pit running longitudinally thereof and forming therebetween suitable trough portions 29 for the 10 accumulation of slag and the proper placing of ingots. Generally speaking, the coke dust 30 is automatically distributed quite uniformly over the bottom, there being no necessity for the workmen to rake or otherwise distribute the coke in a less efficient manner.

This method of distributing coke dust in soaking pits greatly simplifies and improves former methods, and consists in filling the 20 hopper having a removable bottom, then depositing the hopper over the pit, and then lowering the bottom to permit the contents of the hopper to be distributed in a given manner. It will be noted that the hopper 25 as a unit is suspended from the bottom thereof.

There may be various modifications of the invention herein particularly shown and described, and it is my intention to cover all 30 such modifications which do not involve a departure from the spirit and scope of the invention as set forth in the following claims.

I claim:

1. The herein described method which consists in supporting a quantity of pulverulent lining material at the open top of a soaking pit, showering the supported material down upon the bottom of the pit and at the same 40 time directing the material to form a trough of the material upon the bottom of the pit.

2. The herein described method which consists in supporting a quantity of pulverulent lining material at the open top of a 45 soaking pit, showering the supported material down upon the bottom of the pit and causing the material to hill up around the side walls of the pit.

3. The herein described method which consists in supporting a quantity of pulverulent lining material at the open top of a soaking pit, showering the supported material down upon the bottom of the pit, and causing the material to hill up around the 55 side walls of the pit and also diametrically across the bottom of the pit to form troughs at opposite sides thereof.

4. The herein described method of lining soaking pits while in a heated condition, 60 which consists in taking an amount of pulverulent lining material sufficient to line the bottom of the soaking pit and supporting said material at the open top of the pit, showering the material down upon the bottom of the pit, and at the same time causing

the material to cover the entire bottom area of the pit.

5. The combination with a soaking pit, of portable lining distributing means supported over the mouth of the pit and including a 70 hopper to contain a supply of pulverulent lining material, and mechanism for distributing the pulverulent material from the hopper and upon the bottom of the pit as a lining for said bottom.

6. The combination with a soaking pit, of portable lining distributing means supported over the mouth of the pit and including a hopper to contain a supply of pulverulent 80 lining material, and mechanism for distributing the pulverulent material from the hopper and upon the bottom of the pit as a lining thereof and in a trough formation on the bottom of the pit.

7. The combination with a soaking pit, of 85 portable mechanical means for distributing pulverulent material within the pit as a lining for the bottom thereof, and including a frame to rest at opposite sides of the pit, a hopper carried by the frame, and a distributing 90 hopper-bottom capable of being lowered with respect to the hopper to discharge the contents of the hopper into the pit.

8. The combination with a soaking pit, of 95 portable mechanical means for distributing pulverulent material within the pit as a lining for the bottom thereof, and including a frame to rest at opposite sides of the pit, a hopper carried by the frame, a distributing 100 hopper-bottom capable of being lowered with respect to the hopper to discharge the 10 contents of the hopper into the pit, and a hoisting element associated with the hopper-bottom, whereby the hopper may be transported and the hopper bottom lowered and 10 raised with respect to the hopper.

9. A portable distributing hopper for soaking pits, comprising a hopper body, hopper supporting means carried by and extending laterally outward from the hopper 11 body and adapted to rest at opposite sides of the open top of a soaking pit and support the hopper over the top of the pit, a distributing hopper-bottom capable of being lowered with respect to the hopper to discharge the 11 contents of the hopper, and a hoisting element associated with the hopper-bottom whereby the hopper-bottom may be raised and lowered and the hopper transported.

10. The combination of a soaking pit and a portable hopper supported over the mouth of the pit to supply lining material thereto, said hopper being provided with a depressible bottom having means to guide and direct the 1 contents of the hopper when flowing out through the bottom thereof.

11. The combination of a soaking pit and a portable hopper supported over the mouth of the pit to supply pulverulent lining ma-

terial to the pit, said hopper having an open bottom through which the pulverulent material may be discharged, and also provided with a depressible closure for said open bottom, said depressible closure and the open bottom of the hopper being provided with coöperating means to guide and direct the

discharging material and cause the same to hill up around the upright walls of the pit and across the bottom thereof and form the 10 lining material into one or more troughs.

Signed at Duluth, State of Minnesota, this 17th day of October, 1917.

THOMAS D. HODGE.
